GRINDING ATTACHMENT FOR LAWN MOWERS

Filed Jan. 28, 1931

UNITED STATES PATENT OFFICE

LAWRENCE G. HAINES, SR., OF GLASSBORO, NEW JERSEY

GRINDING ATTACHMENT FOR LAWN-MOWERS

Application filed January 28, 1931. Serial No. 511,665.

This invention relates to sharpening devices for lawn mowers and analogous machines and has more especial relation to improvements upon the grinding attachment disclosed in my Patent No. 893,164, issued July 14, 1908.

While the structure disclosed in my aforesaid patent has in practice given excellent results, long and continued use thereof has demonstrated the need of certain additions and changes to enhance its usefulness to the point of maximum efficiency.

As an example, the angular, resilient plate supporting the abrading material in use has the tendency to buckle intermediate its length so that in rotation of the mower blades true contact is not always present. Again, practice dictates that the angular brackets supporting the arcuate arms frequently jar loose. Further, these arcuate arms because of their open ends permit dislodgment of the butterfly nuts employed in connection therewith. Still further, removal when desired of the abrading carrying element is not as convenient as may be.

The leading object of the present invention, therefore, may be said to be the overcoming of these objectionable features and to provide an arrangement, connection, and combination of parts for enhancing the commercial value of the grinding attachment embodying the invention.

With this and other objects in view, the invention consists of the novel construction hereinafter described and finally claimed.

The nature, characteristic features and scope of the invention will be more fully understood from the following description taken in connection with the accompanying drawings forming part hereof, and in which:

Fig. 1 is a cross-sectional view of a lawn-mower having applied thereto the attachment embodying the invention;

Fig. 2 is a view in perspective of the attachment, embodying the invention, detached;

Fig. 3 is a fragmentary view in plan of certain of the parts shown in Fig. 2;

Fig. 4 is a view principally in cross-section of the attachment shown in Fig. 2;

Fig. 5 is a view in perspective of the bracket shown in Fig. 3; and

Fig. 6 is a view in cross-section illustrating a slightly modified form of construction.

For the purpose of illustrating my invention I have shown in the accompanying drawings two forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, there is disclosed a lawn-mower having driving wheels 2, rotary blades 3, a roller 4, and a handle 5, all of which parts may be of any desired construction. Having adjustable relation with the frame 6 which supports the roller 4 are arcuate arms 7, slotted as at 8 throughout the entire length of each arm. The ends of the arms, however, are closed at

each end as indicated by the reference numeral 9. These arms 7 after proper adjustment may be secured to place and permitted to remain upon the lawn-mower during functioning thereof. Arranged to be attached to

and detached from these arms 7 is a rectangular sharpening device capable of adjustment with respect to the arms 7 in a manner to be hereinafter more particularly described.

The rectangular sharpening device comprises a resilient metallic elongated plate 10 having extended upwardly therefrom at its rear the flange 11 to provide a relatively L-shaped structure. The plate 10 at its forward end is turned over upon itself to provide a reinforcing rib 12.

The upper edge of the flange 11 is turned over upon itself as at 13 to provide a reinforcing rib. Both the plate 10 and the flange 11 at their opposed ends are bent over upon themselves to provide reinforcing ribs 14. These reinforcing ribs add strength and relative rigidity to the sharpening device. Fitted to the bottom of the plate 10 and over the rib 12 is a sheet of

abrading material 15, usually of emery cloth.

In practice the abrading material is usually glued to the plate 10. Fitted to the rear of the flange 11 is a thin metal bar 16. This bar is secured centrally of the flange 11 by means of a screw 17 and a nut 18, see Fig. 4. At this point of attachment the screw 17 and nut 18 are utilized for securing in position a leaf spring 19, the free end of which is caused to engage beneath the reinforcing rib 12. The purpose of this leaf spring 19 is to insure relative rigidity of the plate 10, thus tending to maintain the plate 10 closely adjacent the blades 3 in their rotation. In order to provide additional stability to the plate 10, additional leaf springs 20 are provided one upon either side of the leaf spring 18, as best seen in Fig. 2. Having slidable relation with respect to the bar 16 is a pair of oppositely disposed angular brackets 21, each slotted as at 22. The inner ends of each of these brackets is closed as at 24 and the opposite end of each of these brackets terminates in a forked open-ended portion 25. In practice screws 26 and nuts 28 are employed for securing the slotted brackets 21 with respect to the flanged portion of the plate 10. As plainly shown in Fig. 3, substantially U-shaped clamps 29 are fitted over the brackets 21 and the screws 26 caused to pass through these clamps and through the slotted portion of the brackets 21 and through both the flange 11 and the leaf springs 20, whereby with the tightening of the nuts 28 the angular brackets 21 may be secured in adjustable position. The function of the brackets 21 is that of accommodating securing of the attachment as a whole to various sizes of lawn-mowers. By this structure shown in my aforesaid patent, these brackets frequently became loose, and I have discovered that by employing the U-shaped clamps 29 this defect is overcome. In practice the brackets 21 may be permanently attached, if desired, to the arms 7 of the lawn-mower by means of butter-fly nuts 30. However, to facilitate ready removal of the attachment as a whole from a lawn-mower, I have found it convenient to leave the ends of the brackets 21 open as at 25 as before described, whereby it is merely necessary to loosen the butter-fly nuts 30 and withdraw the brackets from the arms 21 without actually removing the butter-fly nuts.

The construction disclosed in Fig. 6 is similar in all respects to that previously described with the exception that the plate holding the abrading material is curved upon its underside as at 31. The above described attachment is adjusted upon a lawn-mower when it is desired to sharpen the rotary blades and is so arranged that as the blades revolve in a backward or reverse movement to that ordinarily used in the cutting of grass, the heel of each knife comes in contact with the abrading surface of the attachment to effect a keen cutting

edge for the blades. By reason of the special resilient features of the combined plate and leaf springs the blades of the lawn-mower contact with the abrading material with just sufficient pressure to effect efficient sharpening without causing the cutting parts of the blades to be unduly worn. In practice it has been demonstrated that very good results may be obtained by sharpening the blades of a lawn-mower by revolving the blades backwardly, as fully set forth in my aforesaid patent.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

What I claim is:

1. A sharpening attachment for a lawn-mower, comprising a relatively resilient plate carrying a sheet of abrading material, said plate having a flange at its rear, the edges of said plate and flange both longitudinally and laterally considered being folded over to provide a reinforcement, a leaf spring secured between the longitudinal reinforcement portions of said flange and plate at each end thereof, and a second leaf spring similarly secured intermediate said first mentioned leaf springs for relatively stiffening the central portion of said plate.

2. A sharpening attachment for a lawn-mower, comprising a relatively resilient plate carrying a sheet of abrading material, said plate having a flange at its rear, the edges of said plate and flange both longitudinally and laterally considered being folded over to provide a reinforcement, a leaf spring secured between the longitudinal reinforcement portions of said flange and plate at each end thereof, and a second leaf spring similarly secured intermediate said first mentioned leaf springs for relatively stiffening the central portion of said plate, and angular slotted brackets adjustably mounted at each end of said flange, the inner ends of said brackets being closed to said slots but having their outer ends open to said slots.

3. A sharpening attachment for a lawn-mower, comprising a relatively resilient plate carrying a sheet of abrading material, said plate having a flange at its rear, the edges of said plate and flange both longitudinally and laterally considered being folded over to provide a reinforcement, a leaf spring secured between the longitudinal reinforcement portions of said flange and plate at each end thereof, a second leaf spring similarly secured intermediate said first mentioned leaf springs for relatively stiffening the central portion of said plate, and pairs of substan-

tially U-shaped clamps for engaging over that portion of each of said brackets which parallels said flange.

4. A sharpening attachment for a lawn mower, comprising a relatively resilient plate carrying a sheet of abrading material, said plate having a flange at its rear, the edges of said plate and flange both longitudinally and laterally considered being folded over to provide a reinforcement, a leaf spring secured between the longitudinal reinforcement portions of said flange and plate at each end thereof, a second leaf spring similarly secured intermediate said first mentioned leaf springs for relatively stiffening the central portion of said plate, and screws and bolts for securing said clamps to place, said screws and bolts serving to secure at least some of said leaf springs to place.
- 20 5. A sharpening attachment for a lawnmower, comprising a relatively resilient plate carrying a sheet of abrading material, said plate having a flange at its rear, the edges of said plate and flange both longitudinally and laterally considered being folded over to provide a reinforcement, a leaf spring secured between the longitudinal reinforcement portions of said flange and plate at each end thereof, a second leaf spring similarly secured intermediate said first mentioned leaf springs for relatively stiffening the central portion of said plate, and an arcuate slotted arm carried by each of said brackets, both ends of each of said arms being closed to said slots.
